CABINET FOR POWDERING AND TURNING
INSIDE-OUT OF RUBBER GLOVESRoy V. Foster and Katherine Foster, Jackson
Heights, N. Y.

Application January 28, 1938, Serial No. 187,428

4 Claims. (Cl. 91—60)

The invention relates to a dust proof cabinet of sheet metal used for the powdering of surgical rubber gloves, as used in hospitals by doctors and nurses. The powder on gloves permits them to be slipped on easily and keeps hands comfortable by absorbing moisture while being worn.

The object of the invention is to confine to a small enclosed space the dust created by the powdering with talcum powder and turning inside out of surgical rubber gloves, preventing contamination of the atmosphere, and thereby safeguarding the health of workers.

In the drawing:

Figure 1 is a view in perspective of a cabinet constructed in accordance with an embodiment of our invention;

Figure 2 is a front elevational view of the device as illustrated in Figure 1 with the front wall omitted;

Figure 3 is a fragmentary detailed sectional view taken substantially on the line 3—3 of Figure 1;

Figure 4 is a fragmentary detailed view partly in section and partly in elevation of the mounting of the electric lamp as herein embodied.

The rectangular cabinet is entirely closed except for the door 1 in lower part of front wall.

A glass window 2 in upper part of front wall permits operator to watch her work.

In the lower part of front wall is a double door 1, fitting well into opening 3 which is shown by dotted line in Fig. 1, and is rendered dust proof by a strip of felt 4, fastened along inside of edge of door. Metal hinges 5, 5, 5 hold door in place at the bottom of cabinet, and metal catches 6, 6 are used to close the door. Talcum powder and gloves are placed into cabinet through this door.

Two round holes 7, 7 allow operator to introduce hands and lower part of arms into interior of cabinet after door is closed. Two canvas sleeves 8, 8, fitting operator's arms on outside of cabinet loosely enough as not to cause discomfort, prevent dust from flying out of cabinet during powdering procedure.

There are two shelves 9, 9 fastened to the inside of cabinet by means of hinges 10, 10. The shelves fold upward and are held when in upright position by means of hinged supports 11, 11 and brackets 12, 12. When folded down, shelves meet in center of cabinet, forming a complete surface. When in this position, shelves are supported by strips of metal 13, 13. Position of supports 11, 11, when shelves are in this position, is shown by dotted lines on right hand side of Figure 2.

With shelves in upright position gloves are shaken around in talcum powder in bottom of cabinet until they are sufficiently powdered. After gloves are powdered, they are placed in right hand side of cabinet; left hand shelf is brought down to horizontal position; excess powder is shaken off gloves; they are placed on shelf. Then right hand shelf is brought down forming complete surface on which to work. The gloves are turned inside out, one by one, and placed on right hand shelf. The left hand shelf is brought into upright position and all gloves are put back into talcum powder on floor of cabinet. The right hand shelf is brought into upright position. Hinges 10, 10 are offset to allow a small space between shelf and cabinet, so that powder collected on shelves while turning gloves slides back into bottom of cabinet as soon as shelves are brought into upright position, rendering shelves self-cleaning. The second powdering is done in same manner as first one described above.

After second powdering is completed, one shelf is brought into horizontal position, excess powder is shaken off gloves, and they are placed on shelf.

Operator removes hands from cabinet and allows powder to settle for a short time, after which the gloves may be removed.

Our invention is intended to be used in hospitals. The rubber gloves worn by doctors and nurses during operations and treatments must be lightly coated with talcum powder. The present procedure of powdering gloves is to sort them according to sizes, place them upon a table, turn them around in a heap of powder, shake off the excess powder, turn the gloves inside out, repowder them, and pack gloves into muslin covers, one pair to each cover. The packages are then ready for sterilization or unsterile use. Large hospitals powder from two hundred to three hundred or more pairs of gloves daily and during this work an enormous amount of dust is created contaminating the atmosphere and settling on clothing, furniture and floors and thereby endangering the health of all workers in the room. The person doing the powdering quite frequently suffers from loss of appetite and respiratory infection in spite of protection afforded by wearing a face mask. The disadvantages of this present method are clearly overcome by the present invention as the cabinet serves to confine the dust created during the powdering and packing of the gloves. With the use of our improved cabinet no separate room is required, no masks need be

worn, and aprons and caps are not required for the protection of hair, clothes, etc.

The cabinet is illuminated by an electric lamp 14, fixed to center of top wall inside of cabinet 5 by means of a porcelain and metal fixture 15. The cable 16 is led through a bushing 17 to outside of cabinet. The light is operated by means of a switch 18 in cable on outside of cabinet. A plug 19 at end of cable connects to wall. A half 10 shade 20 on light protects eyes of operator.

We claim:

1. A means for powdering surgical rubber gloves and the like comprising a cabinet having a window in one of its walls to permit visual access therein, a wall of the cabinet having openings for the insertion of the hands and fore-arms within the cabinet, sleeves carried by said wall defining the openings and arranged exteriorly of the cabinet, shelves within the cabinet, 15 means for hingedly connecting said shelves to opposed walls of the cabinet at a point above the bottom of the cabinet, said shelves when lowered providing a false bottom, means for supporting the free end portion of the shelves 20 when lowered with the shelves substantially coplanar, and means coacting with each of the shelves for holding the same in a raised position.
2. A means for powdering surgical rubber gloves and the like comprising a cabinet having windows in one of its walls to permit visual access therein, a wall of the cabinet having openings for the insertion of the hands and fore-arms within the cabinet, sleeves carried by said wall defining the openings and arranged exteriorly 25 of the cabinet, shelves within the cabinet, means for hingedly connecting said shelves to opposed walls of the cabinet at a point above the bottom

of the cabinet, said shelves when lowered providing a false bottom, means for supporting the free end portion of the shelves when lowered with the shelves substantially coplanar, means coacting with each of the shelves for holding the same in a raised position, and a hinge connection for each of the shelves providing an opening when the shelf is raised to allow powder upon such shelf to fall back upon the bottom wall of the cabinet. 5

3. Means for powdering surgical rubber gloves or the like comprising a cabinet having a window in one of its walls, one of the walls of the cabinet having sleeved openings for the insertion of the hand and fore-arm of a person within the cabinet, shelves within the cabinet hinged to walls thereof, said shelves when lowered being substantially coplanar and spaced from the bottom of the cabinet, and means carried by each of the shelves for maintaining the same raised. 10

4. Means for powdering surgical rubber gloves or the like comprising a cabinet having a window in one of its walls, one of the walls of the cabinet having sleeved openings for the insertion of the hand and fore-arm of a person within the cabinet, shelves within the cabinet hinged to walls thereof, said shelves when lowered being substantially coplanar and spaced from the bottom of the cabinet, and means carried by each of the shelves for maintaining the same raised, the outer end portion of each of the shelves having means engageable with the bottom of the cabinet for supporting said outer portion of the shelf when lowered. 15
